UNITED STATES PATENT OFFICE.

LOUIS STEINBERGER, OF NEW YORK, N. Y.

INSULATOR FOR HEAVY CONDUCTORS.

No. 877,804.

Specification of Letters Patent.

Patented Jan. 28, 1908.

Application filed April 17, 1907. Serial No. 368,744.

To all whom it may concern:

Be it known that I, LOUIS STEINBERGER, a citizen of the United States, and a resident of the city of New York, borough of Brooklyn, in the county of Kings and State of New York, have invented a new and Improved Insulator for Heavy Conductors, of which the following is a full, clear, and exact description.

10 My invention relates to insulators for heavy conductors, and more particularly to a type of insulator used upon electrically operated railways for supporting third rails.

Among the other objects of my invention 15 are the following:

I. To provide a substantially saddle-shaped insulator made practically in one piece;

II. To provide efficient means for securing 20 the insulator to the rail, and readily detaching the same therefrom;

III. To provide means for facilitating the vertical movement of the track structure independently of the rail, thus allowing for 25 depression of the cross ties and track without disturbing the third rail;

IV. To take precautions against loosening the various parts when assembled in position;

V. To reinforce the strength of the insulator body by embedding therein a metallic 30 frame;

VI. To provide various constructional details for improving the general efficiency of the third rail and the track structure immediately associated therewith;

VII. To provide a base or support for the insulator having a hood or shield portion for the purpose of protecting the insulator (from the weather and from mechanical injury).

40 Reference is to be had to the accompanying drawings forming a part of this specification, in which similar characters of reference indicate corresponding parts in all the figures.

45 Figure 1 is a perspective showing a fragmentary rail section as supported by my improved insulator, and the parts occupying their normal relative positions; Fig. 2 is an enlarged vertical section through the body 50 of the insulator and its support, this view showing one of the keys used for locking the rail within the insulator body, and also showing fastening members for preventing removal of the key; Fig. 3 is a substantially 55 central section through the insulator body and rail supported thereby, this view show-

ing the internal construction of the insulator body and also showing the means whereby rigid portions of the track structure are permitted to move freely in relation to the rail 60 and the insulator; Fig. 4 is a fragmentary section upon the line 4—4 of Fig. 2, looking in the direction of the arrow, and showing how the rail keys are fitted against opposite sides of the rail, so as to hold the same within 65 the insulator, and a fastening member which is partly sunken into the keys in order to prevent their removal; Fig. 5 is a perspective of the insulator removed from its supports and from the rail; Fig. 6 is a perspective of one 70 of the keys used for locking the rail within the insulator; Fig. 7 is a perspective of one of the fastening members used for preventing removal or displacement of the keys relatively to the rail body and to the insulator; 75 and Fig. 8 is a vertical section through a rail supported by a slightly different form of insulator employing only a single key for locking the rail relatively thereto.

At 9 is shown a cross tie, and mounted 80 thereupon is a bracket 10 provided at its upper end with a longitudinal head 11 having an opening 12. This head 11 is further provided with two slots 13 which merge into the opening 12, as indicated in Figs. 2 and 3. 85 Bolts 14 extend through the head 11, as indicated in Fig. 3. Each bolt is provided with a head 15 which is sunken into an angular aperture 17 in the head 11. Each bolt 14 is threaded at one end and is fitted with a 90 threaded nut 16, the latter being sunken into an opening 18.

An insulator is shown at 19 and is made up of a body of insulating material, preferably "electrose", into which is embedded a 95 substantially saddle-shaped frame 20 provided with upwardly projecting flanges 21 integral therewith, these flanges having vertical slots 22 parallel with each other.

The insulator as a whole is shown in Fig. 5 100 and may be designated as a substantially saddle-shaped insulating member strengthened by an internal frame of metal. The bolts 14 are threaded through the slots 22 in the flanges 21, so that the insulator with all 105 of the weight carried by it rests upon the bolts 14 and is free to move upward relatively thereto within limits permitted by the depth of the slots 22. The lower portion of the insulator 19 is provided with sheds 23 for facilitating the dripping of moisture, and also to 110 decrease the amount of surface leakage.

The rail is shown at 24 and is held rigidly within the insulator by aid of longitudinal keys 25, 26 which are slipped lengthwise into position. As may be seen from Figs. 3 and 4, these keys conform exactly to the shape of the rail, so as to leave no vacant spaces, and also conform precisely to the internal contour of the adjoining portions of the insulator.

Fastening members 27, of substantially U-shape, as indicated in Fig. 7, are provided for the purpose of preventing displacement of the keys relatively to the insulator. The purpose of these fastening members may be better understood by reference to Fig. 2. These fastening members are simply sprung into slots 30 in the keys and are spaced apart by a distance representing approximately the length of the insulator 19. Each fastening member 27 is provided with portions 28 having proper conformity to fit into the slots mentioned, and is also provided with bent portions 29. When the fastening member is forced into position, the portions 28 are sprung into the relative positions indicated in Fig. 4, and thus grip neatly the keys 25, 26 so as to hold them firmly in relation to the rails and to the insulator.

To remove the insulator from the rail, the fastening members 27 are forced upward, the keys 25, 26 are withdrawn endwise, the bolts are removed from the head of the bracket, and the rail 24 thereupon drops out of the insulator. The insulator together with the bracket may then be removed.

In the form shown in Fig. 8 the rail 24^a is supported by the insulator 31, these parts being in a great measure similar to the rail 24 and insulator 19. Instead of having two keys, however, only one key 32 is provided, and instead of a fastening member 31, a pin 33 is used for substantially the same purpose.

I do not limit myself to the use of any prescribed insulating material. I prefer, however, to employ the insulating material known in the art as "électrose." Neither do I limit myself to the exact form nor to the precise arrangement of any or all of the parts herein shown and described, as various changes may be made, which will readily occur to those skilled in this art, without departing from the spirit or scope of my invention.

Having thus described my invention, I claim as new and desire to secure by Letters Patent:

1. An insulator for heavy conductors, comprising a substantially saddle-shaped body portion, provided with an opening for receiving a rail, and further provided with flanges projecting therefrom and having slots, a bracket provided with a head having slots into which said flanges project loosely, and bolts threaded through said slots of said flanges and engaging said head so as to support said body portion.

2. The combination of a bracket provided with a head having an opening and also having slots merged into said opening, an insulator mounted loosely within said opening and provided with flanges extending loosely into said slots, said flanges being provided with slots, and bolts mounted upon said head and extending through said slots of said flanges so as to support said insulator loosely from said bracket.

3. An insulator for heavy conductors, comprising a body of insulating material, provided with an opening for receiving a rail, and a metallic strengthening member following generally the contour of said body of insulating material and embedded centrally therein for the purpose of strengthening the same.

4. An insulator for heavy conductors, comprising insulating body portion for supporting a rail, and a substantially saddle-shaped metallic member embedded centrally within said body portion and having a flange projecting from said body portion for the purpose of supporting the same.

5. An insulator for heavy conductors, comprising an insulating member for holding a conductor, said insulating member being provided with a plurality of flanges of metal projecting therefrom and disposed parallel with each other along the general length of the conductor, for the purpose of supporting said insulating member and said conductor.

6. As an article of manufacture, a substantially saddle-shaped member of insulating material provided with an opening for receiving a rail, and a strengthening member of metal also substantially saddle-shaped and embedded centrally within said member of insulating material, said metallic member being provided with portions projecting from said member of insulating material for the purpose of supporting the same.

7. An insulator for heavy conductors, comprising a substantially saddle-shaped member for holding a rail, a key for engaging said rail and said substantially saddle-shaped member, and a fastening member for holding said key in a predetermined position relatively to said saddle-shaped member.

8. An insulator for heavy conductors, comprising a supporting member provided upon its under side with an opening, a saddle-shaped insulating member mounted within said opening and movable vertically in relation to said supporting member, and means for mounting within said insulating member a rail having its tread portion downward.

In testimony whereof I have signed my name to this specification in the presence of two subscribing witnesses.

LOUIS STEINBERGER.
